United States Patent Office.

JOHN COYNE, OF ALLEGHENY CITY, PENNSYLVANIA.

Letters Patent No. 94,286, dated August 31, 1869.

IMPROVED APPARATUS FOR THE MANUFACTURE OF PIG-BLOOM.

The Schedule referred to in these Letters Patent and making part of the same.

To all whom it may concern:

Be it known that I, JOHN COYNE, of Allegheny City, in the county of Allegheny, and State of Pennsylvania, have invented a new and improved Iron-Manufacturing Apparatus; and I do hereby declare that the following is a full, clear, and exact description thereof, which will enable others skilled in the art to make and use the same, reference being had to the accompanying drawing, forming part of this specification.

This invention relates to an improved apparatus, to be used in iron-smelting and refining establishments, for receiving the molten metal from the furnaces and moulding it into blooms, pigs, or slabs, as required, and delivering it when sufficiently cooled.

And the invention consists in the combination and arrangement of the parts of the apparatus, as will be hereinafter more fully described.

Figure 1 represents a plan view of my improved apparatus, with a part of the moulds or receivers turned over, as in discharging the pigs or slabs.

Figure 2 represents a sectional elevation of the same, taken on the line $x-x$ of fig. 1.

Similar letters of reference indicate corresponding parts.

A represents a circular metallic table, having a large central opening, arranged to revolve horizontally upon balls B, on a circular-grooved stand C, the bottom of the said table being also grooved to rest on the balls.

A circular flange, D, projects downward from the table, inside of the stand, and is toothed at the bottom, the teeth gearing with a driving-pinion, E, which imparts the motion. These teeth may be either arranged, as shown, to receive motion from a pinion working in a vertical plane, or they may be arranged to gear with a wheel working horizontally from a vertical shaft.

The table may also be arranged to work on conical radial rollers, if preferred, instead of the balls B.

F represents a hoop or band of iron, attached to the outside of the table A, and projecting below the top of the stand C, which, together with the inner-projecting flange D, serves to prevent the molten metal, which may escape between the boxes or moulds, and run down upon the table, from getting into the groove of the stand, or upon the balls; they also prevent, in like manner, other matter from entrance to the groove.

G represents moulds or receiving-boxes, placed radially on the top of the table A, and shaped so that the sides fit together as closely as may be conveniently done.

They may be made of iron, or any other suitable substance, and shaped to give to the metal which flows therein any required form, as pigs, blooms, or slabs;

they may also be divided into two or more compartments, if preferred.

These moulds are jointed, at their outer ends, to bolts H, running diagonally through the table A, to the inside, where they are connected to spring-supports I, for the inner ends of the moulds, consisting of metallic plates, rising vertically from the inside of the table, and bent over near the upper ends, so that the said ends rest in the corner of an annular recess in the upper face of the table, as shown at K.

These bent ends press the topmost parts, whereon the moulds rest, outward, slightly from the face of the table, and produce a springing action against the nuts L.

Keys may be used, instead of the nuts, for holding the bolts, if preferred.

The bottoms of the moulds are provided with bevelled studs M, which, when the said moulds are thrown back, after dumping, strike against the sides of the rounded or bevelled tops of the spring-supports I, and thereby relieve the said moulds from the severe shocks that would occur in falling upon rigid supports.

The said moulds are also provided with other projections, N, to facilitate dumping them, by a bar placed under them, and resting on the top of the supports I, for a fulcrum, and operated by the attendant standing within the circle of the rotating table.

The tops of the supports I are recessed, as shown at O.

To prevent the metal from flowing down between the boxes upon the carriage or table, I provide the T-shaped guards, shown at P, to be placed between the moulds, so that the bent flanges thereof will lap over the adjacent edges of the moulds.

The apparatus, thus constructed, is so placed, relatively to the furnace, that the melted metal may readily flow therefrom into the moulds, and solidify therein while being carried around from the place of receiving to the place of cooling, where it is discharged by the attendant using a lever, as above described.

At the discharging-place, a curved rail, R, is so placed that the upper edges S of the outer ends of the moulds will strike thereon with force, and dislodge the metal, when of such a nature as to stick in the moulds.

This apparatus is designed more especially for use in such refining-furnaces as are used in the direct production of wrought-iron from cast-iron, by a rapid process of decarbonization, by the use of oxides, but is applicable to other furnaces.

I do not claim a moving or revolving table, with moulds or boxes, in combination with spouts, so as to form pig-blooms of molten metal and oxides, or other materials.

Having thus described my invention,

What I claim as new, and desire to secure by Letters Patent, is—

1. The moulds, hinged at the outer ends to the bolts H, connected to the spring-supports I, and all combined with the table A, and arranged as specified.
2. The arrangement of the bevelled projections M, on the moulds, and the spring-supports, substantially as specified.

3. The flange D and hoop E, combined with the table A and stand C, substantially as specified.

4. The combination, with the moulds G, of the T-shaped guards, substantially as specified.

JOHN COYNE.
